United States Patent

Des. 242,333
Patented Nov. 16, 1976

242,333

SECURITY ALARM DEVICE

Wayne T. Wise, Box 175, Frankfort, S. Dak. 57440

Filed Dec. 12, 1975, Ser. No. 640,062

Term of patent 14 years

Int. Cl. D10—05

U.S. Cl. D10—106

FIG. 1

FIG. 2

FIG. 3

FIG. 4

FIG. 1 is a view in perspective of a security alarm device showing my new design as seen from the front, one end, and top;

FIG. 2 is a view in rear elevation thereof;

FIG. 3 is a view in end elevation of the end opposite that seen in FIG. 1; and

FIG. 4 is a view in bottom plan thereof.

I claim:

The ornamental design for a security alarm device, substantially as shown.
